UNITED STATES PATENT OFFICE

2,083,806

REVOLVING TIRE SIGN AND COVER

Ray B. Anderson, Oklahoma City, Okla.

Application January 16, 1937, Serial No. 121,009

3 Claims. (Cl. 40—41)

This invention relates to improvements in display devices, particularly for advertising purposes, and an object of the improvement is to provide a novel device of this character which is especially adapted to be disposed on or in association with an automobile spare tire casing or cover.

Another object of the invention is to provide an advertising display device adapted to be operated from a running part of the vehicle propelling mechanism for automatically exhibiting a number of revolving signs in successive order.

An additional object of the invention is to provide a display device of the revolving sign type in which a plurality of rotatable sign bearing cards or disks are grouped in relatively overlapping relation at the correspondingly split ends and so rotated that the bottom or innermost disk of the group is caused, when completely rotated, to appear at the top or outer end of the group.

Other objects and advantages of the invention are obtained by the means and mechanism hereinafter more fully described with reference to the accompanying drawings wherein:

Figure 1 is a front elevation of the device.

Figure 2 is an end elevation thereof.

Figure 3 is an enlarged detail view of the lapped lower ends of the sign disks with associated mechanism shown in one position of operation.

Figure 4 is a view similar to Fig. 3 but showing the mechanism in another position of operation.

Figure 5 is a detail view of the lower or compact end of the disk support.

Figure 6 is a detail view, in perspective, of a crank element of the disk-rotating mechanism.

Figure 7 is a detail view of one of the sign disks.

The device is mounted on the rear end of a motor vehicle in combination with the spare tire cover thereof by a suitable bracket 1 having a horizontal spindle tube at its upper end and being provided at its lower end with a bearing 3 for supporting the outer end of the main drive shaft 4 which is adapted to be continuously and rotatively driven by a suitable connection at its other end with the fan belt or other moving part of the motor vehicle. At the other end of shaft 4 is a drive pulley 5 having a driving connection through a belt or cable 6 with a large fan pulley 7 rotatable on spindle 2. Pulley wheel 7 has a hub or sleeve 8 upon which is also fixed a smaller pulley 9, the latter being connected by cable 10 with a large pulley 11 rotatable on a stub shaft fixed near the lower end of bracket 1. Pulleys 7 and 9 are so proportioned that they

make one complete revolution for every quarter turn of the pulley wheel 11.

Mounted for rotation upon the outer portion of the central tube are a number of sign disks 12, 13, 14 and 15. Although but four sign disks are shown in the accompanying drawings, it is to be understood that the device may be constructed to operate more or less disks, as desired. Each sign disk is constructed, as shown in Fig. 7, with a circular body portion of smaller radius than the pulley 7 and having a small central aperture 9 to receive the central tube. These disks are adapted to be provided on their respective outer faces with suitable display and advertising matter and they are provided each with a narrow radial slot 15 17 opening outwardly from the central aperture 16 through the peripheral edge of the disk. The disks are grouped side by side on the spindle with the slotted portions directed downwardly and with the corresponding ends *a* laterally on said tube and in overlapping relation with the corresponding opposite ends *b* so that when a bottom or inner sign, such as the disk 12, is turned through a complete revolution it will be on the top or outer side of the group. Depending from the spindle 2, behind the disk, is a hanger rod 18 at the lower end of which is a compact frame 19 extending crosswise of the lower slotted portions of the disk with the upper horizontal member 20 providing a rest or support for the downwardly flexed spring hooks 21 at the peripheral edges of the disk portions *a*. The disks are normally positioned upon the horizontal member 20 so that the spring hooks 21 of all but the innermost disks are pressed inwardly against their corresponding edges; the spring hook of the innermost disk depending downwardly through an opening 22 in frame member 20 with the hook end thereof in position forwardly of the lower frame member 23 to be engaged by and to be moved through one complete revolution with one arm 24 of a crank pin 25.

The crank pin 25 is journalled crosswise in the pulley wheel 7 near the edge thereof with the arm 24 disposed outwardly of the forward face of the wheel disk 7 and with its other arm 26 disposed outwardly of the rear face of said wheel 7. A spring connection 27 between the wheel 7 and the crank pin 25 tends to hold the crank pin 25 in the position indicated in full lines in Fig. 3 to abut the spring hook of the innermost disk of the group depending below the bottom member 23 of the compact frame. The rotation of the sign disk is regulated by a trip mechanism 55

including a spring tensioned slide 28 mounted in the lower portion of bracket 1 and extending crosswise of the upper edge of pulley 11 with an inwardly disposed depending cam follower lug 29 overlying the outer face of the said pulley and having an outwardly disposed depending end lug 30 adapted to be moved, by a cam 31 on the outer face of pulley 11, in and out of the circular path travelled by the crank pin arm 26 during the rotation of wheel 7. The cam 31 is designed to continuously contact the follower lug for three quarters of a revolution of pulley 11 to thereby hold the slide 28 displaced, against the tension of its spring, to the right of Fig. 2 so that for three revolutions of the wheel 7 the crank pin arm 21 will be caused to jump over the depending hooks of the bottom or innermost sign disk when the crank pin is rotated about its axis by the abutment of the crank end 26 with the lug 30 of the slide. On the fourth turn of the pulley 7, the rear end of the cam 31 passes beyond the follower 29, whereupon the slide is shifted by spring pressure to the right of Fig. 2, withdrawing the abutment lug 29 out of the pass of the crank pin arm 26. Hence, on the fourth turn of the wheel 7, the crank pin arm 24 engages the spring hook of the bottom sign disk 12 and propels the same forwardly through the opening 22 in the frame and through a complete revolution; the disk being released at the completion of the turn by reason of the crank pin being again rotated about its axis by abutment of the crank pin end 26 with the slide lug 29, the latter having been in the meantime again shifted to the right by action of cam 31 in time to effect the release of the sign disk 12 when the latter is at the outer side of the sign group.

Carried by the wheel 7 and trailing the crank pin 25 is a roller 32 which is adapted, during the rotation of the wheel 7, to roll over and press against the inner spring tensioned end 33 of a lever 34 pivoted at 35 to the frame 19 and having a spring pressed roller 36 at its opposite end. In the horizontal position of the lever, as shown in Fig. 3, the spring pressed roller 36 presses against the outermost sign disk, such as the disk 15 in Fig. 3 for the disk 12 in Fig. 4, when the latter has been moved from the inner to the outer side of the sign group. When the roller 32 of the wheel 7 comes into contact with the inner end of the lever, it moves the same upwardly, as shown in Fig. 4, and causes the spring pressed roller 36 at the operative end to be lowered to engage and force the end of the outermost disk inwardly of the frame 19.

By means of the mechanism described, the sign disks 12, 13, 14 and 15 are successively moved from the inner to the outer side of the sign group with a rotary motion for displaying their respec-

tive advertising matter. By reason of the cam mechanism and the gear ratio a new sign will be displayed every fourth revolution of the wheel 7 and will be moved from the inner to the outer side of the group in one revolution of the wheel. The main drive shaft 4 is placed at will into and out of driving relation with respect to the revolving sign mechanism by a conventional clutch means 37.

What is claimed is:—

1. A display device comprising a plurality of radially split sign disks disposed one against another in a compact group for rotation about a common axis, the corresponding ends of the disks at one side of the split overlapping the adjacent corresponding disk end at the opposite side of the split whereby when the innermost disk of the group is rotated through a complete turn it will be moved to the outermost side of the group, and means for rotating said disk to cause the innermost disk of the group to be rotated successively to the outermost side of the group. 10

2. A display device comprising a plurality of radially split sign disks disposed one adjacent another in a compact group for rotation about a common axis, corresponding ends of the said disks at one side of the split overlapping the adjacent corresponding disk ends at the opposite side of the split whereby when the innermost disk of the group is rotated to a complete turn 15 it will be moved to the outermost side of the group, a member mounted for rotation concentrically with respect to said disk, means for imparting continuous rotation to said members, means carried by said member and engaging said disk for imparting rotation thereto, and means for placing the innermost disk successively in position to be engaged by the means carried by said member for rotation therewith. 20

3. A display device comprising a plurality of 40 radially split sign disks disposed one against another in a compact group for rotation about a common axis, the corresponding ends of the disk at one side of the split overlapping the adjacent corresponding ends of the disk at the opposite 45 side of the split whereby when the innermost disk of the group is rotated through a complete turn it will be moved to the outermost side of the group, a driving member mounted for rotation concentrically with respect to said disk, 50 means for imparting continuous rotation to said member, a pin carried by said member, projections on said disk to be engaged by said pin for rotating the disk with the said member, and means for placing the projections of the said disk 55 successively in engagement with the said pin beginning with the innermost disk.

RAY B. ANDERSON.
